UNITED STATES PATENT OFFICE

169,648

TRAY

Anton Zaic, Queens Village, N. Y.

Application December 27, 1950, Serial No. 13,598

Term of patent 7 years

(Cl. D44—10)

To all whom it may concern:

Be it known that I, Anton Zaic, a citizen of the United States, residing in Queens Village, in the county of Queens and State of New York, have invented a new, original, and ornamental Design for a Tray, of which the following is a specification, reference being had to the accompanying drawing, forming part thereof.

Fig. 1 is a top plan view of a tray embodying my new design.

Fig. 2 is a side elevational view thereof; and

Fig. 3 is a partial sectional view taken generally along line 3—3 of Fig. 1.

Fig. 4 is a perspective view of a tray embodying my new design.

I claim:

The ornamental design for a tray, as shown.

ANTON ZAIC.
